UNITED STATES PATENT OFFICE.

JOHN FRETZ, OF ANGEL, CALIFORNIA.

IMPROVED FURNACE AND APPARATUS FOR TREATING PYRITOUS ORES.

Specification forming part of Letters Patent No. 25,500, dated September 20, 1859.

To all whom it may concern:

Be it known that I, JOHN FRETZ, of Angel, Calaveras county, State of California, have invented a new and Improved Apparatus for Desulphurizing and Carbonizing Pyrites; and I do hereby declare the following to be a full, clear, and exact description of the same, reference being had to the accompanying drawings, and to the letters of reference marked thereon.

My invention consists in an apparatus, fully described hereinafter, whereby the desulphurizing and oxidizing of pyrites, through the agency of heat, currents of air, and a jet or jets of steam, is so gradually and efficiently accomplished that the removal of the valuable metals from the pyrites by any amalgamating process is facilitated.

In order to enable others to make and use my invention, I will now proceed to describe its construction and operation.

On reference to the accompanying drawings, which form a part of this specification, Figure 1 is a plan view of my improved apparatus for oxidizing and desulphurizing pyrites of iron containing valuable metals; Fig. 2, a sectional elevation on the line 1 2, Fig. 2; Fig. 3, the same on the line 3 4; Fig. 4, an end view, looking in the direction of the arrow, Fig. 1; Fig. 5, a sectional elevation on the line 5 6; Fig. 1.

Similar letters refer to similar parts throughout the several views.

A is a furnace having ordinary grate-bars, a fire-door, b, ash-pit B, and an opening, d, for the escape of the products of combustion to a flue, which will be especially alluded to hereinafter. Passing longitudinally through this furnace at a point a suitable distance above the fire, and at a slight inclination, is a cylinder or tube, C, on the front end of which is a circular collar having a V-groove adapted to V-shaped rollers d' d', the spindles of which revolve on the opposite edges of the trough E, which is furnished with a supply of water to keep the rollers and their journals cool. The cylinder C, near its opposite end, rests on rollers e, which also revolve in water contained in a trough. A spindle, c, is secured to the end of the cylinder, and is furnished with an ordinary handle, by means of which, or by means of any suitable system of gearing connected with a steam-engine or other prime mover, the cylinder may be turned. From a pulley on the

spindle c extends a strap round a similar pulley on the shaft f, which passes longitudinally through and turns within the stationary cylinder F, the latter being secured, in an inclined position, to the top and on one side of the furnace. This spindle f is furnished with a worm, h, the threads of which fit as closely as possible to the inside of the cylinder without causing undue friction.

It will be seen that the stationary cylinder F is situated directly above the flue G, through which the products of combustion pass from the outlet d of the furnace to the chimney. This cylinder is furnished at its lower end with a hopper, I, and near the latter with an air-opening, i. Near the opposite end of the cylinder is a small tube, j, communicating with the chimney, and near the extreme end of the cylinder another tube, k, communicating with the revolving cylinder C. It will be seen that the latter is furnished on the inside with spiral ridges or corrugations extending from end to end. The lower end of this cylinder terminates within and communicates with a vertical box or chamber, J, (see Fig. 5,) to the lower end of which is connected the end k' of a steam-pipe. This vertical box or chamber communicates, through an opening, m, near the top, with another vertical chamber, K, and the latter, through a pipe, n, with a third vertical chamber, L, which is furnished at the top with a tube, M, having an ordinary throttle-valve. Each of these boxes has at the bottom a sliding door, for the double purpose of regulating the draft and removing the contents of the chambers. The quartz and pyrites, having been reduced, as is usual, in a stamping-mill, are first placed on the top of the furnace, which is provided with retaining-ledges. After the powdered pyrites are dried and partially roasted they are placed into the hopper I, and, dropping from thence into the cylinder F, are carried gradually through the latter by the revolving worm until they arrive at the tube k, through which they pass into the revolving cylinder C. Now, it will be observed that the stationary cylinder F is submitted to considerable heat by being stationed over the flue G, and this heat has the effect of desulphurizing the pyrites, the fumes of sulphur passing out from the cylinder through the pipe j to the chimney. A draft is maintained through the cylinder by means of the air-hole i, and thus the contents are sub-

mitted to a current of air, which, combined with the heat, has the effect of oxidizing the pyrites. After the partially desulphurized and oxidized pyrites pass into the rotating cylinder C, which is immediately over the hottest part of the fire in the furnace, they are agitated by the spiral ribs of, and maintained in motion during its passage through, the cylinder, thus exposing every particle to the heat, as well as to the current of air which passes through the cylinder. The pyrites, now more fully desulphurized and carbonized, fall from the end of the rotating cylinder into the box J in a heated condition, and in falling through this box, being brought in contact with a current of air and steam, the latter entering through the pipe k' and the former through the door at the bottom of the box, are fanned by the current of air, so that the combustion of whatever sulphur remains will be continued by the oxygen of the air and the oxidizing process by the steam. The heavier particles of pyrites desulphurized and oxidized by the above process will fall to the bottom of the box J, while the lighter particles will pass through the opening m into the box K', where they meet another current of air, which has the effect of carrying off any remaining fumes of sulphur, the particles of pyrites falling to the bottom of this box. The still finer particles will be carried to the third box through the pipe n, and be acted upon by the air in a similar manner, the remaining fumes of sulphur, if any, passing through the tube M to the external air. The desulphurized and oxidized pyrites are removed at pleasure from the various boxes and submitted to any of the amalgamating processes usually adopted for separating the valuable metals which are mixed with them. It will now be seen

that from the time the pyrites are first placed to dry and roast above the furnace until they have passed to the boxes, the desulphurizing and oxidizing process continues gradually, by being submitted to gradually increasing heat combined with the currents of air and steam. This gradual process is absolutely necessary for effectually and rapidly attaining the desired end, inasmuch as a quick and violent heat would tend to cause the sulphur and iron to form a flux, in which case the gold or other valuable metal in the pyrites would become so thoroughly embodied that its extraction would be a matter of great difficulty.

Without claiming the separate use of the devices herein described, I claim as my invention, and desire to secure by Letters Patent—

1. The hollow stationary cylinder F, its revolving worm, and its openings for the admission of the pyrites and the introduction of air and discharge of the fumes of sulphur, in combination with the rotating cylinder C and its internal ribs, the said stationary and rotating cylinders communicating with each other through a pipe, k, and the whole being arranged in respect to the furnace A, substantially as and for the purpose set forth.

2. The system of vertical boxes or chambers J, K, and L, communicating with each other, with the steam-pipe K', the rotating cylinder C, and the exit-pipe M, and arranged substantially as set forth, and for the purpose specified.

In testimony whereof I have signed my name to this specification in the presence of two subscribing witnesses.

JOHN FRETZ.
